Primary Examiner — Prabhakar Deshmukh(57) **CLAIM**

The ornamental design for a mount for electronic devices, as shown and described.

DESCRIPTION

FIG. 1 is a front, side, and top perspective view of a mount for electronic devices embodying the new design; FIG. 2 is a back, side, and bottom perspective view thereof;

FIG. 3 is a front view thereof;

FIG. 4 is a back view thereof;

FIG. 5 is a top view thereof;

FIG. 6 is a bottom view thereof;

FIG. 7 is a first side view thereof, the second side view being a mirror image; and,

FIG. 8 is a front, side and top perspective view thereof, shown in environmental use.

The broken lines depict unclaimed portions of the design and form no part of the claimed design. The broken lines in FIG. 8 indicate environmental cable and form no part of the claimed design.
